UNITED STATES PATENT OFFICE.

ALONZO W. SPOONER, OF PORT HOPE, ONTARIO, CANADA.

DESIGN FOR A METAL BAR.

SPECIFICATION forming part of Design No. 20,507, dated February 3, 1891.

Application filed January 8, 1891. Serial No. 377,170. Term of patent 14 years.

To all whom it may concern:

Be it known that I, ALONZO W. SPOONER, a subject of the Queen of Great Britain, residing at the town of Port Hope, in the county of 5 Durham, in the Province of Ontario, Canada, have produced a new and original Design for Bars of Babbitt or other Metal, of which the following is a specification, reference being had to the accompanying drawing, which shows 10 a perspective view of a bar or ingot of metal cast according to my design.

The leading feature of my design consists of a base having a series of transverse grooves beneath the same and a series of truncated cones above, said cones and grooves being so arranged that each groove is under the space 15 between two cones.

Referring now to the details, A represents the base having a series of grooves *aa* beneath 20 the same and extending across the entire under side of said base. Supported by and formed

on said base are several short truncated cones B B. These cones should be so arranged that the first one from the end should be upon that part of the base that is between the end thereof and the groove nearest the end, while the other cones should be each formed upon a portion of the base between two grooves; or, in other words, the grooves *aa* should not be directly under the cones, but under the spaces 25 between the cones, as shown.

I should regard a bar in which the cones were grooved or ribbed as within the spirit of my design.

What I claim is—

The design for a metal bar herein shown and described.

Port Hope, Canada, December 8, 1890.

ALONZO W. SPOONER.

In presence of—

CHARLES C. BALDWIN,
JOHN E. CAMERON.
